FIG. 1 is a perspective view of my poncho hoodie;
FIG. 2 is a front view thereof;
FIG. 3 is a right side view thereof;
FIG. 4 is a left side view thereof;
FIG. 5 is a rear view thereof;
FIG. 6 is a top view thereof; and,
FIG. 7 is a bottom view thereof.

The broken lines shown in the drawings illustrate portions of my poncho hoodie that form no part of the claimed design.
